(57) **CLAIM**

The ornamental design for a horizontal octagonal eyeglass lens with vertical ovular aperture, as shown and described.

DESCRIPTION

FIG. 1 is a front environmental view of a horizontal octagonal eyeglass lens with vertical ovular aperture showing my new design;

FIG. 2 is a front perspective view of the horizontal octagonal eyeglass lens with vertical ovular aperture;

FIG. 3 is a front view thereof;

FIG. 4 is a rear view thereof;

FIG. 5 is a right side view thereof with a left side being a mirror image; and,

FIG. 6 is a top view thereof with a bottom view being a mirror image.

The broken lines are included for illustrative purposes only and form no part of the claimed design.
